UNITED STATES PATENT OFFICE.

ENOCH W. AUSTIN, OF SHAWNEE, OKLAHOMA.

LINK-FORMING MACHINE.

Application filed April 25, 1921. Serial No. 464,211.

To all whom it may concern:

Be it known that I, ENOCH W. AUSTIN, a citizen of the United States, residing at Shawnee, in the county of Pottawatomie, 5 and State of Oklahoma, have invented certain new and useful Improvements in a Link-Forming Machine, of which the following is a specification.

This invention relates to link forming 10 machines, and more specifically to an improved machine for forming chain-links from lengths of wire.

One object of this invention is to provide a simple, compact, comparatively inexpensive and thoroughly practical machine by 15 which chain-links can be quickly and easily formed for hooking into one another so as to construct a chain of the sprocket-chain type.

20 Other objects and advantages will be pointed out or implied in the following details of description, in connection with the accompanying drawings in which:

Fig. 1 is a vertical sectional view, the section being taken substantially along the line 25 1—1 of Fig. 2, portions being omitted for the sake of clearness.

Fig. 2 is a top plan view of the device, the frame being omitted, and parts of the 30 machine being broken away.

Fig. 3 is a view somewhat similar to Fig. 2, but some of the working parts being differently positioned.

Fig. 4 is a view somewhat similar to Fig. 35 1, but the sections being taken substantially through the center or along the median plane of the machine.

Fig. 5 is a perspective view illustrating the working end of one of the wire-bending 40 members.

Referring to these drawings in detail, in which similar reference characters correspond with similar parts throughout the several views, and in which the supporting 45 frame A may be of angle iron, as illustrated, or of any appropriate construction and material, the invention consists in the construction and arrangement of parts, as will now be described and claimed as follows:

50 A sheet metal bed or plate 6 is provided with apertures 7 through which rivets or bolts may extend for securing the plate 6 to the frame A, although any appropriate means may be employed for securing the 55 plate 6 to the frame A. This plate is pro-

vided with a substantially central opening 9 through which a lever 10 operates, this lever being pivoted at 11 and including a bowed arm 12 which passes up and down through the opening 9 when the lever 10 is 60 swung on its pivot. On opposite sides of the opening 9, a pair of bearings 13 are secured by means of bolts 14 which extend through the plate 6 and have their heads substantially flushed with the upper side of 65 the plate 6. Three abutments 15, 16 and 17 extend up from the upper side of the plate 6, these abutments being each provided with a shank which extends down through the plate 6, and nuts are threaded on these 70 shanks for removably securing the abutments in fixed position on the plate or bed of the machine. The abutments 16 and 17 are provided with plane surfaces or edges 75 which face one another and are slightly spaced to receive, one at a time, lengths of wire B and to hold the middle portion of wire straight while the wire is bent into U-shape by a pair of levers 18 of the special construction illustrated in Fig. 5; that is, 80 each lever 18 is provided with a flange or abutment 18^a which is substantially one-half the thickness of the lever, and adjacent to this abutment each lever 18 is provided with a depression which terminates in a hump 85 18^b. Although it is possible to form each lever 18 of a single piece of material, it is preferable to form each lever 18 of two strips of metal and riveting or otherwise securing them together as illustrated, thereby avoiding unnecessary machining of the lever. 90 Moreover, each lever 18 is provided with an aperture 18^c through which a bolt 19 extends, these bolts 19 also extending through a strap or keeper 20 and through the plate 95 6, nuts being provided on these bolts to secure them in place. At the opposite side of the aperture 9, from the abutments 15, 16 and 17, a bolt 21 extends through the plate 6 and through a guiding plate or strip 100 22 which may be curved as shown, and the rear ends of this strip may be secured to the plate 6 by means of bolts 23. Spacing blocks or washers 24 are provided between the strip 22 and plate 6 for holding the 105 strip in spaced relation to the plate or bed 6, this space being but slightly greater than the thickness of each lever 18, so that these levers can be quickly and easily swung from the starting position shown in Figs. 1 and 110

2 to the operating position shown in Figs. 3 and 4. While being thus swung, the levers 18 are held so close to the plate 6 that the wire B cannot pass under the levers, but is forced by the latter into the U-shape illustrated in Fig. 3. Of course, the abutments 15, 16 and 17 coact with these levers 18 for thus forming the wire, the humps 18^b pressing the wire against the narrow portion 5 of the abutment 16 and against the relatively narrow abutment 15, while the relatively wide abutment 17 limits the narrowing of the bight portion of the U-shape wire, so that the free ends of each wire can be 10 passed through and hooked in the bight portion of a similarly shaped wire after these free ends have been bent to form hooks in the manner which will presently be explained. Moreover, during this primary 15 bending of the wire, the flanges or abutments 18^a extend over the wire and hold it against or adjacent to the plate 6, so that it cannot be disengaged from the abutments 16 and 17 around which it is bent. In Fig. 20 25 3, one of the levers 18 is shown at the end of its operating stroke, the other one of these levers having been retracted so as to more clearly disclose the wire B with respect to the abutments 15, 16 and 17.

30 Now, referring to Fig. 4, it will be seen that the lever 10 has been swung from the starting position shown in Fig. 1 to the final operating position. In swinging to this position, the bowed arm 12 moves upward 35 through the aperture 9 and presses the free ends of the wire B upward against the abutments 18^a; thereby bending these free ends over the abutments 18^a to form hooks 40 for engagement with the bight portion of a similar wire or link. When the links have been hooked together, their respective hooks 45 can be closed by any appropriate means (not shown). When lever 10 and both the levers 18 are retracted from the final operating 50 position, the flanges or abutments 18^a are withdrawn from the hooks of the wire or link, and the latter is free to be lifted from the machine, so that another length of wire can be placed between the abutments 16 and 17, for bending in the manner previously 55 described.

The lever 10 may be provided with an aperture 10^a, and any appropriate means may be engaged with these levers for yieldably holding it in the position shown in Fig. 1. Moreover, any appropriate means

may be provided to operate the levers 10 and 18 by other than manual power.

The lever 10 is provided with notches or depressions 10^b which receive the free ends 60 of the wire B and hold them in properly spaced relation during the formation of the hooks.

Although I have described this embodiment of my invention very specifically, it 65 is not intended to limit this invention to these exact details of construction and arrangement, but changes may be made within the scope of the inventive idea, as implied and claimed. 70

What I claim as my invention is:—

1. In a link forming machine, a plate having an opening therethrough, an abutment having a straight side facing said opening, an abutment having a straight side facing the first said straight side and narrowly spaced therefrom so as to hold a length of wire in position to be bent while preventing the portion of wire between the abutments from being bent, a pair of levers pivoted on 80 said plate and operable to bend said wire into U-shape while bringing the ends of the wire over said opening, each of said levers including an abutment which overlies said wire during the bending of the latter, and a lever pivotally mounted on the under side of said plate and including a bowed arm in position to pass up through said opening and over the abutments of said pair of levers and to 85 bend said wire over the latter abutments. 90

2. In a link forming machine, a frame, a plate secured horizontally on said frame and provided with an opening, bearings on opposite sides of said opening, a lever having a bowed end held between and pivoted to said bearings, said bowed end being provided with spaced notches, means including a pair of levers for bending a length of wire into U-shape and thereby bringing the end portions of the wire over said notches, said levers being provided with abutments which extend over the wire and hold it in position to be bent, and means to hold the pair of levers against said plate while said first lever is pressing the free ends of the wire against the abutments of said pair of levers and coact with the latter, for forming hooks 100 in said wire. 105

In testimony whereof, I affix my signature.

ENOCH W. AUSTIN.
